MACHINE FOR APPLYING METALLIC LEAF TO BOOK-COVERS OR THE LIKE.

1,190,961.

Specification of Letters Patent. Patented July 11, 1916.

Application filed April 24, 1913. Serial No. 763,281.

To all whom it may concern:

Be it known that I, CHARLES E. SMITH, a citizen of the United States, residing at Oak Lawn, in the county of Providence and State of Rhode Island, have invented a new and useful Machine for Applying Metallic Leaf to Book-Covers or the like, of which the following is a specification.

My invention relates to an improved machine for depositing metallic leaf upon book covers or the like from a package roll, and it consists in the means hereinafter fully described by which the right amount of metallic leaf is drawn from the roll containing it and applied to the book cover or other article.

In the accompanying drawing: Figure 1 represents a front elevation of the machine. Fig. 2 represents a top view of the same. Fig. 3 represents a side view. Figs. 4 and 5 represent detail views of the adjustable means for drawing the paper strip forward to the extent required. Fig. 6 represents an enlarged detail view showing the depositing means in its open position. Fig. 7 represents the same when in its first closed position. Fig. 8 represents a section taken in the line 8, 8, of Fig. 6. Fig. 9 represents the same when in its second closed position. Fig. 10 represents the same when in its third closed position in which the deposited metallic leaf will be separated from that remaining in the roll. Fig. 11 represents a detail view showing an edge view of the package roll, and a forward end view of the depositing jaw. Fig. 12 represents a section taken in the line 12, 12, of Fig. 10. Fig. 13 represents a section taken in the line 13, 13 of Fig. 10. Fig. 14 represents the application of suction to the depositing jaw. Fig. 15 represents a detail section taken in the line 15, 15, of Fig. 14. Fig. 16 represents a plan view of the under side of the depositing jaw.

In the drawing A represents the frame of the machine, B the driving shaft upon which is placed the bevel pinion C, the said shaft B being driven from the pulley D on the shaft E by means of a worm and worm gear. The support for the book cover or other article to which the metallic leaf is to be applied is formed by the reciprocating and rocking jaw F which is joined to a sliding block G held for reciprocation between the guide-ways H, H, of the frame,

the said jaw being operated in its up and down and rocking movement, by means of the crank pin I, attached to the disk I', which is keyed to the end of the shaft B. The support for the strip of metallic leaf which is drawn from the roll by mechanism to be described is formed by the depositing jaw J provided with a shank K which is guided in its vertical movement by the guide-ways L, L, and is forced downward by means of the spring M against the stoppin N, which is inclosed by the slot O in the said shank. The shank K of the depositing jaw J, is held between the said guide-ways L, L, by means of the latch piece P, which is pivoted at the screw Q, and limited in its pivotal movement by means of the pin R. The package roll of metallic leaf S is held for rotation upon a stud T, attached to the shank K, and is held upon said stud by means of the spring U as shown in Fig. 12.

In Fig. 9, the rocking jaw F and the yielding jaw J, are represented in their highest position with the paper strip and metallic leaf which has been drawn from the package roll S, pressed flatly between them; but the continued movement of the crank pin I will cause the deflection of the rocking jaw F and a slight backward movement at the angular edge V of the depositing jaw, whereby the metallic leaf W which at this point is under the supporting paper strip X will become crushed or disintegrated and thereby cause the separation of the portion Y when deposited upon a book cover from the portion Z, which remains with the package roll.

In order to prevent the falling of the metallic leaf W from the supporting paper strip X when the same is held in the position shown in Figs. 6 and 7, I provide the face a of the depositing jaw J with openings b, b, which connect with the vacuum chamber c, from which the air is drawn by means of the suction pipe e, as shown in Figs. 14, 15 and 16.

The book cover is placed upon the jaw F when the same is in the position shown in Fig. 6 and is then carried up to contact with the depositing jaw J to receive the deposit of metallic leaf, as shown in Fig. 7. The construction of the sliding block G to which the rocking jaw F is jointed, is shown in the section Fig. 8.

In order to be able to feed the strip of metallic leaf between the jaws F and J and to vary the length of the strip of metallic leaf to be deposited upon the book covers, 5 as desired, I provide a rubber covered feed roll f, shown in Figs. 2, 3, and 4, which is driven from the shaft B, by means of the bevel pinion C, the bevel gear g, the oblique shaft h, the bevel gear i, and the bevel pinion j. Upon the shaft k, which is held 10 in sliding boxes l, l, so as to be movable toward and from the feed roll f, is secured the cams m, m, which contact with the end flanges m' of the roll f, and which serve to 15 impart an outward movement to the said shaft k against the resilient action of the actuating spring n of the sliding boxes, and upon said shaft k is placed the adjustable feeding segments o, o, which when brought 20 into contact with the feed roll f serve to draw the paper strips and metallic leaf forward from the package rolls, S, S. The said paper X, X, from which the metallic leaf has been deposited are slightly held 25 against the periphery of the feed roll f, by means of the rollers p, p, which are secured to the loose shaft q.

A gear a' fast on the roll f, and driven 30 from the gear i, engages a gear b' on the shaft k. The dimensions of the gears a' and b' are such that the peripheral speed of the roll f, to which the gear a' is attached, is the same as the peripheral speed of the segments o attached to the shaft k. 35 The rollers p, p, bear very slightly against the paper strip upon the feed roll, and serve merely to keep the strips in place when they are not engaged by the segments o and they do not operate to cause the forward 40 movement of the paper strips with the continuously moving periphery of the feed roll.

The cams m, m, slidably contact with the flanges m' of the feed roll f, but do not rotate the latter. The segments o, o, are made 45 adjustable upon the shaft k, with reference to the position of the cams thereon, and with relation to each other, by means of the clamp d', and by means of such adjustment 50 the segments may be caused to engage for a greater or less extent with the feed roll f. During the time that the segments o, o, are not in contact with the roll f they do not feed the strip, and while the high portion 55 of the cam m is in contact with the flange m' the book support is being lifted up against the strip and the operation of attaching the gold leaf to the book is accomplished; during this time the segments o, o, 60 are not in contact with the roll f. The segment o may be so adjusted that a portion of it passes by the roll f during this period, but whatever amount of the segment o is, by the presentation of the depressed portion 65 of the cam m to the flange m' of the

roll f, allowed to come in contact with the strip on the roll f so much of the segment feeds the paper strip and by adjusting the segment on the shaft k the amount of the segment in contact with the roll f and the consequent feed of the paper strip may be varied. The depositing jaws J, J, and the accompanying package rolls of metallic leaf S, are adjustably secured to the slotted projecting bracket r by any suitable means. 70

When the machine is set in operation the adjustable feeding segments o, o, will be carried forward through the action of the springs n of the sliding boxes l, l, to surface contact with the paper strip upon the feed roll f, and cause a length of the paper strip to be advanced, the length of which advance is determined by the radial adjustment of the feeding segments on the shaft k. This adjustment may be measured by marginal graduations t on the segment faces, and if desired, some fixed member adjacent the segment such as the cross bar u may be employed as the relatively fixed point for such adjustment. The paper strip in its 80 passage over the angular edge V of the depositing jaw, and between the rubber covered feed roll f, and the peripheries of the segments o, develops a degree of frictional electricity which requires removal in order 85 to properly dispose of the said strip, and to this end the paper strip X is passed over a hot metal plate v, which may be heated by means of an electric heater w. The driving clutch x is carried into engagement by 90 pressing down upon the pedal, y, and is withdrawn from engagement by the resiliency of the spring z, and may be automatically disengaged at the completion of its 95 cycle of revolution. 100

Supplementary to the main advantages of the machine already disclosed by the description in laying metallic leaf automatically from a single strip, the following advantages will be noted in the use of the machine for applying leaf from a plurality of strips. In many instances, as in book cover gilding, the gold should be laid in as many transverse parallel lines thereon as there is intended to be lines of gold lettering, and these lines are often and usually of length differing from each other because of the difference in the number of words, ornaments, or letters contained in each particular line. 110

One advantage of the machine is the capacity to lay a plurality of strips simultaneously as well as automatically. Another advantage is to space the gold leaf according to the spacing of the lines on the book. A third advantage is to start the application 120 of the gold leaf at the several different necessary distances in from the right hand margin of the cover. A further advantage is to end the application of the several leaves 125 necessary different distances in from the left 130

hand margin of the cover. Another advantage is that I am enabled to maintain the several supporting strips in parallelism on the machine and prevent their accidental disengagement therefrom.

- 5 The first advantage above referred to is attained by laying the book or book cover or article on the support F transversely of the lines of travel of the gold leaf strips; 10 and then having a plurality of supports J, corresponding with the number of lines required by the particular book cover, arranged in series on the bar r. In the present case, three supports only are shown simultaneously controlling three strips X for 15 application to three lines. Therefore, there must be, as shown, three segments o, to transversely draw forward or feed the three strips.
- 20 The second enumerated advantage is attained by making the supports J longitudinally adjustable to each other on bar r. This bar has a longitudinal slot a² through which loosely pass bolts a³ whose heads a⁴ 25 rest upon washers a⁵ on the bar, and whose threaded ends enter threaded cavities a⁷ (see Fig. 11) in the guides or hangers L. Between the bar and each hanger is a bolster a¹⁰ embracing the bar and provided 30 in its lower face with a seat a¹¹ for the member L. The bolster is provided centrally with an oblong slot lengthwise of the bolster (not visible in the drawings) through which the bolt a³ passes. By loosening the bolts it 35 will be seen that the three supports may be slid longitudinally of the bar r and be clamped thereon at any distance required to register with any line on the book cover. This adjustment is facilitated by the scale 40 a¹² on the bar r.

The third enumerated advantage is attained by the transversely adjustable character of the supports J relatively to each other in the line of travel of the strips X, 45 whereby the V-shaped ends of the supports, which coöperate with the jaw F to cut and initiate the application of the severed gold leaf, extend to the right different distances. To effect the transverse movement of the 50 members L it will be observed that the slot a² is much broader than the bolt a³, and the central oblong slot in the bolster is provided. For the purpose of simultaneously adjusting all of the supports J relatively to 55 the right hand margin of the book cover or article, the end of the bar r is provided with transverse slots a¹³ to accommodate adjusting screws a¹⁴ engaging in threaded holes a¹⁵ in the machine frame.

60 In attaining the fourth advantage the following elements enter, namely, the length of the section of severed gold leaf and the distance that its supporting strip had previously been advanced by the bolt of its 65 particular cam. The length of each pull is

equal to the length of the particular line on the book to be covered by the particular leaf, which as already suggested, often does not correspond with the length of the remaining lines. To initially determine the 70 length of pull, the line on the book is first measured and that measurement in inches determines the degree in inches of the radial adjustment of the particular feeding segment o. It is advantageous, but not es- 75 sential to employ supports J having the exact lengths of the several cut leaf lengths. A supply of shoes or supports J of different lengths, and the readily adjustable character of the members L, K, makes substitution easy.

The fifth advantage above enumerated is attained by the scale b² on the cross-bar u, used in conjunction with the scale a¹² on the arm r. That is, the relative locations of 85 the supports J are determined on the latter scale, and the several segments o and rolls p are then located at corresponding distances on the scale b². It is important that the segments and supports be arranged in 90 alinement because should they be by accident arranged substantially otherwise the strips X would assume diagonally disposed positions across the machine, and would be accidentally released from the 95 segments when the elevations of the cams m were in contact with the flanges m'.

I claim as my invention:

1. In a metallic leaf applying machine, the combination of a support for a strip of 100 metallic leaf, a support for an article to which the leaf is to be applied, and means for imparting a rocking movement to one of the said supports substantially as described.

2. In a metallic leaf applying machine, 105 the combination of a support for effecting the deposit of metallic leaf upon an article to which it is to be applied and a support for the said article, with means for imparting a rocking movement to one of the said 110 supports, and means for causing a sliding movement between the said supports, substantially as described.

3. In a metallic leaf applying machine, the combination of a support for effecting 115 the deposit of metallic leaf upon an article to which it is to be applied, a support for the said article, means for rocking one of said supports, and means for feeding the metallic leaf between the said supports, substantially as described.

4. In a metallic leaf applying machine, the combination of a support for effecting the deposit of metallic leaf upon an article to which it is to be applied, a support for 125 the said article, a continuous leaf supporting strip movable between the supports and suction means applied to one of the supports, substantially as described.

5. In a metallic leaf applying machine, 130

- the combination of an adjustable segment, a feed-roll, and means for causing the engagement of the segment with the said roll, to draw a paper strip forward, substantially as described. 5

6. In a metallic leaf applying machine, the combination of an adjustable segment provided with graduations, a feed roll, means for causing the engagement of the 10 segment with the said roll to draw a paper strip the distance required, and a cross-bar for locating the working position of the segment on its holding shaft, substantially as described.

15 7. In a metallic leaf applying machine, the combination of a reciprocating support for an article to which a metallic leaf is to be applied, with a yielding support for depositing the metallic leaf thereon, and 20 means for rocking one of said supports, substantially as described.

25 8. In a metallic leaf applying machine, the combination of a support for effecting the deposit of metallic leaf upon an article to which it is to be applied, a support for 30 the said article, and a sliding box and crank movement for reciprocating and rocking the said support, substantially as described.

35 9. In a metallic leaf applying machine, the combination of a support for effecting the deposit of metallic leaf upon an article to which it is to be applied and a support for the said article, means for rocking one 40 of said supports with means for holding the package roll of metallic leaf in connection with the depositing support, substantially as described.

45 10. A metallic leaf applying machine having in combination a holder for a roll of metallic leaf, a support for an article to which the leaf is to be applied, a support for the metallic leaf and its supporting paper strip, means for feeding the metallic leaf between said supports, and means for reciprocating both supports in the same plane.

50 11. A metallic leaf applying machine having in combination a holder for a roll of metallic leaf, a reciprocating support for an article to which the leaf is to be applied, a hollow support for the metallic leaf and its supporting paper strip having openings through its face, devices to draw air inwardly through said opening, means for feeding the metallic leaf and its supporting paper strip between said supports, and means for reciprocating said supports, substantially as described.

55 12. A metallic leaf applying machine having in combination a holder for the roll of metallic leaf, a brake to retard the rotation of said rolls, a support for an article to which the leaf is to be applied, a support for the metallic leaf and its supporting paper strip, means for feeding the metallic 60 strip between said supports, and means for longitudinally adjusting the segment on the shaft, substantially as described.

65 13. A metallic leaf applying machine having in combination a holder for the roll of metallic leaf, a support for the article to which the leaf is to be applied, a support for the strip of metallic leaf, means for feeding the metallic leaf between said supports including adjustable devices for varying the length of strip fed, and means for bringing together and separating said supports, substantially as described. 70

75 14. A metallic leaf applying machine having in combination a holder for the roll of metallic leaf, a support for the article to which the leaf is to be applied, a support for the strip of metallic leaf, means for feeding the metallic leaf between said supports, means for bringing together and separating said supports and rocking one of said supports with relation to the other, substantially as described. 80

85 15. A metallic leaf applying machine having in combination a holder for the roll of metallic leaf, a support for the article to which the leaf is to be applied, a support for the strip of metallic leaf, adjustable means for feeding the metallic leaf between said supports, and means for bringing together and separating said supports and rocking one of said supports with relation to the other, substantially as described. 90

95 16. A metallic leaf applying machine having in combination, a holder for a roll of metallic leaf, a rocking support for an article to which the leaf is to be applied, a support for the metallic leaf and its supporting strip provided with an edge, means for feeding the metallic leaf and its supporting strip between said supports in contact with said edge, and means for bringing the rocking support into contact with said edge to sever the metallic leaf upon the strip substantially as described. 100

105 17. A metallic leaf applying machine having in combination a holder for the roll of metallic leaf, a support for the article to which the leaf is to be applied, a support for the strip of metallic leaf, means for holding said strip against the face of said support, adjustable means for feeding the strip of metallic leaf forward over the face of the said support, and means for bringing together and separating said supports, substantially as described. 115

120 18. In a metallic leaf applying machine, the combination of a feed roll, a shaft parallel with the feed roll, a segment on the shaft in engagement with the feed roll to draw a paper strip the distance required, and means for longitudinally adjusting the segment on the shaft, substantially as described. 125

19. In a metallic leaf applying machine, the combination of a resilient support for a strip of metallic leaf, a reciprocating support for an article to which the leaf is to be applied adapted to engage the first support in its reciprocation, and means for reciprocating the second support in the same plane as the first named support.
20. In a metallic leaf applying machine, the combination of a plurality of supports for effecting the deposit of metallic leaf upon an article to which it is to be applied, a single support for said article engageable with all the supports, and means for imparting a rocking movement to the support for the article.
21. In a metallic leaf applying machine, the combination with the frame, of a horizontal bar upon the frame, a plurality of supports for metallic leaf mounted on the bar, a reciprocating member movable to and from the supports slidably mounted in the frame adapted to support an article to which the leaf is to be applied, and means for reciprocating said member.
22. In a metallic leaf applying machine, the combination with the frame, of a horizontal bar upon the frame, a support for a strip of metallic leaf on the bar, a reciprocating member in the frame movable to and from the support adapted to support an article to which the leaf is to be applied, feeding mechanism adapted to draw the strip across the support, and means actuating said member for operating the feeding mechanism.
23. In a metallic leaf applying machine, the combination with the frame, of a horizontal bar upon the frame, a plurality of supports for strips of metallic leaf upon the bar, a reciprocating member movable to and from the supports mounted in the frame and adapted to support an article to which the leaf is to be applied, a feed roll rotatably mounted in the frame adapted to engage the strips, a shaft rotatably mounted in the frame adjacent the feed roll and coöoperating therewith, segments on the shaft adapted to engage the strips on the feed roll to advance the strips, and means actuating said member for operating the feed roll.
24. In a metallic leaf applying machine, the combination with the frame, of a bar upon the frame, a plurality of supports for the strips of metal leaf upon the bar, means for adjusting the supports longitudinally of the bar, a reciprocating member for supporting an article to be operated on slidably mounted in the frame, a feed roll rotatably mounted in the frame over which the strips pass, a shaft rotatably mounted in the frame adjacent the feed roll and operated thereby, segments mounted for longitudinal adjustment on the shaft engaging the strips against the roll, means for longitudinally adjust-
- ing the segments to coöperate with the supports, and means actuating said member operating the feed roll.
25. In a metallic leaf applying machine, the combination with the frame, of a bar upon the frame, a plurality of supports for the strips of metallic leaf upon the bar, means for adjusting the supports transversely of the bar, a reciprocating member for supporting an article to be operated on movable to and from the supports, and means for actuating said member.
26. In a metallic leaf applying machine, the combination with a frame, of a horizontal, forwardly extending arm upon the frame, means for transversely adjusting the bar, a plurality of supports for strips of metal leaf upon the bar, a reciprocating member for supporting an article to be operated upon movable to and from the supports, means for advancing the strips over the supports, and means for reciprocating said member.
27. In a metallic leaf applying machine, the combination with the frame, of a supporting bar mounted on the frame, a hanger attached to the bar, a shank slidably mounted upon the hanger, a jaw upon the end of the shank provided with a beveled end and a stud in the shank for supporting a roll of metallic leaf.
28. In a metallic leaf applying machine, the combination with the frame, of a supporting bar on the frame, a hanger attached to the bar, a stop pin in the hanger, a shank slidably mounted in the hanger and provided with a vertical slot to receive the pin, a jaw upon the lower end of the shank provided with a flat bottom face and a pointed end, a stud in the shank for supporting a roll of metallic leaf, and resilient means for pressing the shank against the stop pin.
29. In a metallic leaf applying machine, the combination with the frame, of a supporting bar on the frame, a hanger attached to the bar, vertical guides on the hanger, a stop pin in the hanger, a shank slidably mounted in the hanger between the guides and provided with a vertical slot to receive the pin, a jaw on the lower portion of the shank provided with a sharp edge at one end, a stud in the shank above the sharp edge for supporting a roll of metallic leaf, a spring engaging the hanger and the shank, a latch pin on one guide, and a latch pivotally mounted on the other guide engaging the latch pin.
30. In a metallic leaf applying machine, the combination with the frame, of a supporting bar on the frame provided with a slot, a bolster upon the bar provided with a slot and with a seat, a hanger seated in the bolster, a bolt in the hanger passing through the slots, a head on the bolt, a washer between the head and the face of the bar, a

shank slidably mounted on the hanger, a jaw upon the end of the hanger, and a stud in the shank for supporting a roll of metallic leaf.

5 31. In a metallic leaf applying machine, the combination of a frame, of a horizontal bar in the frame, supports for strips of metallic leaf on the bar, vertical guide ways in the frame, a slidable block in the guide ways, a jaw pivotally attached to the block and extending below the supports, and a crank member engaging the jaw.

10 32. In a metallic leaf applying machine, the combination of a support for a strip of metallic leaf, a support for an article to which the leaf is to be applied, and means for imparting a reciprocating movement to one of the supports in the same plane as the other support, said supports being engageable with each other in such reciprocation, substantially as described.

15 33. In a metallic leaf applying machine, the combination with the frame, of a roll shaft mounted in the frame, a feed roll mounted on the shaft, flanges on the shaft, bearing boxes slidably mounted in the frame adjacent the shaft and movable toward the shaft, resilient means for forcing the boxes toward the shaft, a cam shaft mounted in the boxes, cams on the cam shaft engaging the flanges, segments on the cam shaft adapted to cooperate with the feed roll, driving connections between the shafts, and means for driving one of the shafts.

20 34. In a metallic leaf applying machine, the combination with the frame, of a roll shaft rotatably mounted in the frame, a roll on the shaft, flanges on the roll shaft, a cam shaft slidably mounted in the frame and movable toward the roll shaft, cams on the cam shaft adapted to engage the flanges, resilient means in the frame for forcing the

25 cams into engagement with the flanges, segments on the cam shaft, clamping members on the cam shaft engaging the segments, operative connections between the shafts, and means for driving one of the shafts.

35. In a metallic leaf applying machine, the combination with the frame, of a roll shaft rotatably mounted in the frame, a roll 50 on the shaft, flanges on the shaft, a shaft mounted in the frame above the feed roll, gravity rolls supported by the second shaft adapted to rest upon the feed roll, a third rotary shaft yieldingly mounted in the 55 frame adjacent the roll shaft, segments on the third shaft in alignment with the gravity rolls coöperating with the rolls, a gear on the roll shaft, a gear on the third shaft engaging the first gear, and means for actuating the roll shaft.

36. In a metallic leaf applying machine, the combination of a segment, a feed roll, and means for causing the engagement of the segment with the feed roll to draw a 65 paper strip the distance required.

37. In a metallic leaf applying machine, the combination of a plurality of segments, a feed roll, and means for causing the engagement of the segments with the feed roll 70 to draw the several paper strips the varying distances required.

38. In a metallic leaf applying machine, the combination of a feed roll, a shaft parallel with the feed roll, a segment on the 75 shaft in engagement with the feed roll to draw a paper strip the distance required, and means for radially adjusting the segment on the shaft, substantially as described.
